UNITED STATES PATENT OFFICE.

WASHINGTON I. TUTTLE, OF BALTIMORE, MARYLAND.

BOX OR RECEPTACLE.

No. 853,844.

Specification of Letters Patent.

Patented May 14, 1907.

Application filed May 10, 1905. Serial No. 269,772.

To all whom it may concern:

Be it known that I, WASHINGTON I. TUTTLE, a citizen of the United States, residing at Baltimore, in the State of Maryland, have invented new and useful Improvements in Boxes or Receptacles, of which the following is a specification.

My invention has relation to new and useful improvements in boxes or receptacles, and more particularly to boxes the walls of which are formed of sections which are secured to each other by suitable connecting devices to provide a continuous wall; and the primary object of the invention is to provide a box which is extremely simple in construction, inexpensive of production and durable in use.

A further object of the invention is to provide a box of the character mentioned, the bottom and walls of which may be constructed from a single blank of material, preferably sheet-metal, and to provide a novel and improved means for securing the meeting edges of the wall sections together without the use of solder.

A further object of the invention is to provide a box, the bottom and side walls of which may be struck up from a single blank of material so formed that blanks for boxes of various depths may be cut without the necessity of providing cutting dies of different sizes.

Briefly and generally stated, the invention resides in providing in a box structure of the character set forth, an improved means for uniting the meeting edges of the upstanding walls or wall-sections of the box, which means consists of a connecting device and outstanding members or projections struck out of the body of the walls and engaged by said device to hold the walls in rigid relation to each other, said members being preferably located at points removed from the meeting edges of the walls.

I have fully and clearly illustrated my invention in the accompanying drawings to be taken as a part of this specification, and wherein—

Figure 1 is a plan view of the blank from which the box is made. Fig. 2 is a perspective view of the completed box, the hinged cover being thrown back. Fig. 3 is a sectional view through a corner of the box and

the fastening device for the walls, said section being taken on a line through the outstanding members on the walls, the view showing the parts in position before the connecting-piece is pressed down. Fig. 4 is a view similar to Fig. 3, after the corner connection has been finished. Fig. 5 is a perspective view of the corner before the connecting-piece is applied in position to unite the walls. Fig. 6 is a perspective view of the connecting piece. Fig. 7 is a plan view of the blank from which the hinge for the cover of the box is formed. Fig. 8 is a perspective view of the cover removed from the box with the hinges attached thereto.

Referring to the drawings and more particularly to Fig. 1, the reference numeral 1 designates a blank of sheet metal from which the box is to be made, said blank being of a size to produce a box of the dimensions and capacity desired. The particular form of blank shown in the drawings for the purposes of this application, is cut to produce a rectangular receptacle, and as so cut consists of the rectangular bottom section 2, having formed integral therewith end wings 3, and side wings 4, said wings, when the box is formed, being bent up at an angle to the plane of the bottom to constitute the end and side walls 5 and 6 of the box, as shown in Fig. 2. In the form of box shown in the drawings, the end and side walls 5 and 6 are bent at right angles to the bottom 2, and it will be seen that said walls assume positions at right angles to each other to form a rectangular box. The meeting edges of the walls of the box, or those edges which abut each other when the box is formed, are cut on continuous straight lines so that when the wings are bent up to provide the walls for the box, said adjacent straight edges of the end and side walls will meet to form a close joint from top to bottom of the walls, and also assist in lending rigidity to the box when completed.

In order to provide a smooth and neat edge for the box, I prefer to turn or fold the free edge of each of the side and end wings over and down into the box. These turned or folded over portions are indicated by the reference numeral 5^a in Fig. 2 of the drawings.

I will now proceed to describe the novel and improved means which I have devised,

for rigidly connecting the meeting edges of the box walls. This means consists broadly of outstanding members arranged on the outer side of the body of each of the walls at points adjacent the vertical edges thereof, but removed a short distance therefrom, which members are, when the box is completed, engaged by a connecting-piece, which clamps the walls to each other. In the drawings I have shown the outstanding members just referred to, as being provided by punching each wall section adjacent to the edge which is to be secured to the edge of an adjacent wall, to form tongues 7, the free ends of which are at first directed toward the edge of the wall, but which are afterward bent back upon the body of the wall as shown in Fig. 5, so as to take a position reverse to that they originally assume, and in such a manner as to project at an angle to the wall to leave a space 8 between them and the wall, for a purpose to be hereinafter stated. It will be perceived upon reference to the drawings, that the tongues are formed with their bases, or the points at which they are attached to the walls, removed from the vertical meeting edges of the walls, and this is done in order that said edges may closely engage each other to form a close joint at the corner of the box. Another advantage which might be stated at this point to be gained by forming the tongues from the body of the blank with their bases located at a point removed from the edges thereof, is that no especially formed dies or punches will be required to cut the edges of the walls, which, as heretofore stated, are perfectly straight, which permits the said edges to be cut by an ordinary cutter, no matter what depth box is to be made and the tongues need no especially constructed punch in their formation. The advantages just stated not only add greatly in producing a satisfactory article, but also simplify to a large extent the process of manufacture.

A material saving of stock, which is an item of great importance in the extensive manufacture of boxes, is effected by striking up the tongues from the material of the walls of the box at points removed from the abutting edges of such walls, or with the basis of the tongues removed from such edges as described.

In the drawings each wall is shown provided with two outstanding members, which are arranged in vertical alinement, but it will be understood that in a deeper box a greater number of said members may be employed, or in a shallow box, one of the members may be dispensed with.

The connecting-piece for engaging the tongues 7 to unite the meeting edges of the walls, consists of a strip or body 9 of sheet metal bent at an angle along a central longitudinal line 10, to provide wings 11, each of

which is bent inwardly at its free edge to provide inturned engaging flanges 12. The flanges 12 are practical counterparts of the tongues 7; that is to say, the free ends of the flanges point in an opposite direction to that in which the free ends of the tongues 7 are directed, so that when the locking element is in position, the tongues and flanges are interlocked, the free ends of the tongues entering in behind the flanges, and the free ends of the flanges entering in behind the tongues. The connecting piece, as just described, is adapted to be fitted to the corner of the box walls, on the outside thereof, the corner of said connecting-piece receiving the meeting ends of the walls and the wings 11 lying one in engagement with each of the walls, the inturned flanges 12 engaging beneath the outstanding members of the box-walls. The connecting-piece is applied to the corner by placing the inturned flanges at one end thereof in engagement with the ends of the tongues, and then by thrusting the piece lengthwise until the tongues are entirely engaged and the corner completely covered. In order to provide a rigid joint, and to prevent the said connecting-piece from sliding out of engagement with the tongues, I flatten the connecting-piece by a press or other suitable means, so as to bring the piece and tongues into close engagement, the inturned flanges 12 being bent down upon the wings 11, to grasp and tightly hold the tongues, and the latter pressed down upon the box walls to hold said inturned flanges.

It will be seen that in applying the connecting-piece the meeting edges of the walls are drawn together into engagement with each other so as to form a close joint at the corner, and that when the connecting-piece is pressed down, it effectually closes the openings in the box wall from which the tongues have been punched.

By constructing a box in the manner herein shown and described, it will be seen that there are no projecting parts on the interior thereof at the corners. This is of special importance, since it is often desirable to line the side walls of boxes of this class, with paper or cardboard, and it will be apparent that if there were interior projecting parts at the corners, it would be extremely difficult to secure a neat and close fit of the lining material, especially if this material was composed of stiff paper or cardboard.

The manner of connecting the box walls will also be found advantageous in that it permits a wider range of decoration than in those boxes the walls of which are united by solder. The sheet material employed in the manufacture of these boxes is usually lacquered or enameled prior to the formation of the box and it will be readily seen that by the use of the corner fastening shown and described, there is no danger of the ornamenta-

tion being melted, smoked or otherwise disfigured, as is the case in the soldering process where heat is absolutely necessary.

While the construction herein shown and described is more especially applicable to the manufacture of boxes made from sheet metal, still I do not wish to be understood as limiting myself to this material alone, for it will be obvious that the blank may be made from ordinary paper box-board without departing from the spirit of the invention. In this case, however, I will employ the same metallic corner fastening devices as used in the metal box, and these will add great strength and rigidity to the finished structure.

The box is shown provided with a hinged cover 13, which may or may not be provided with the surrounding flange 14. This lid is hingedly connected to one of the walls of the box and for this purpose, I have shown a simple and effective form of hinge, which will now be described. In Fig. 7 I have shown a blank from which this hinge is formed, said blank consisting of an intermediate strip portion 15, at the opposite ends of which and integral therewith are formed transverse attaching members 16, lying at right angles to said strip portion and parallel to each other, said members extending equal distances on either side of the strip portion. In order to form the hinge the strip portion is bent at a point along its longitudinal center to bring the opposite ends of each of the transverse members 16 into facial contact with each other. The strip portion 15 when bent as above described, is shaped to provide a loop 17 which is adapted to receive a pivot or pintle 18, carried by the edge of the lid, said pivot being formed by a rod extending longitudinally of said edge and secured thereto by bending portions of said edge about the rod to maintain it in position. The hinge is secured to the box wall by forming spaced horizontal slots 19 in said wall at the point at which it is desired to attach the hinge thereto, and the ends of each of the members 16 are then passed from the outside of the box in through one of said slots and said ends are then separated and bent in opposite directions so as to be spread apart to assume positions flat against the inner face of the box wall, on opposite sides of the slot therein so that said members cannot be withdrawn through the slot and the hinge and cover will be effectively secured to the box wall. By this construction it will be seen that the attaching members of the hinge are located entirely within the box and are therefore hidden entirely from view from without, which adds greatly to the general appearance of the box.

Having thus described my invention, what I claim as new and desire to secure by Letters Patent is:—

1. In a box structure, side walls each having integral offstanding corner locking elements removed from the ends of said walls, and corner fasteners each having integral engaging elements co-operating with the first 70 named elements and constructed when in position to draw the ends of adjacent side walls of the structure into contact with each other to form a close joint at the corners of the box. 75

2. In a box structure, side walls having integral offstanding corner locking elements whose bases are removed from the ends of said walls, but which are parallel therewith, and a corner fastener having integral engaging 80 elements interlocked with the first named elements.

3. In a box structure, side walls having integral corner locking elements whose bases are removed from the ends of said walls, and 85 a corner fastener having integral engaging elements interlocked with the first named elements.

4. In a box structure, side walls having integral tongues stamped therefrom at points 90 adjacent the meeting ends of said walls, and a corner fastener having integral engaging elements interlocked with the said tongues.

5. In a box structure, side walls having integral corner locking elements whose bases 95 are removed from the ends of said walls, and a corner fastening strip having integral engaging elements, interlocked with the said elements on the walls, said strip when in position covering the meeting edges of adjacent 100 walls.

6. In a box structure, side walls having integral corner locking tongues stamped from the said walls, the bases of the tongues being removed from the end edges of the walls, and 105 a corner fastening strip having integral engaging elements interlocked with said tongues, said strip when in position covering the meeting edges of adjacent walls of the box.

7. A box consisting of a blank having a 110 body portion and integral side and end wings constituting the vertical walls of the box, the opposite ends of each wing being provided with integral outstanding tongues whose bases are removed from the end edges 115 of the wings, and separate corner fastenings for the corners of the box, each consisting of an angular strip having inturned flanges interlocked with the said tongues, the said corner fastening strips being located outside 120 the box.

8. The herein described blank for a box, consisting of a body portion having integral side and end wings, the opposite ends of each wing being provided with integral outstanding 125 tongues, whose bases are removed from the end edges of the wings, said tongues being adapted to interlock with corner fastening pieces.

9. In a box, side walls having abutting 130

edges and free-ended corner locking elements struck up from the material of the walls, the bases of which are removed from and whose free ends are turned away from the 5 edges of the walls, and a corner fastener having counterpart locking elements to interlock with those of the side walls.

In testimony whereof I have hereunto set my hand in presence of two subscribing witnesses.

WASHINGTON I. TUTTLE.
